CLAIM

The ornamental design for a telephone set, as shown and described.

DESCRIPTION

FIG. 1 is a perspective view from above of the top and one side of a telephone set in closed position showing new design;

FIG. 2 is a bracketed perspective view of the set showing the underside of handset and the upper inside surface of the stand;

FIG. 3 is a side elevational view thereof as in FIG. 1, the side view opposite being a mirror image;

FIG. 4 is a top plan view thereof;

FIG. 5 is a bottom plan view thereof;

FIG. 6 is a front elevational view thereof; and

FIG. 7 is a rear elevational view thereof.
